UNITED STATES PATENT OFFICE.

FRANK S. WILLIAMS, OF KENDAIA, NEW YORK.

GANG-PLOW.

1,157,136.

Specification of Letters Patent.

Patented Oct. 19, 1915.

Application filed September 10, 1914. Serial No. 861,118.

To all whom it may concern:

Be it known that I, FRANK S. WILLIAMS, a citizen of the United States, residing at Kendaia, in the county of Seneca and State of New York, have invented certain new and useful Improvements in Gang-Plows, of which the following is a specification.

My invention relates to improvements in gang-plows, and has particular reference to such plows so constructed that the plow-shares thereof may be reversed for throwing the soil laterally in opposite directions, the same being particularly well adapted for use in plowing vineyards, while in no sense 15 restricted to such use alone.

An important object of the invention is to provide a gang-plow of the above mentioned character, which is comparatively simple in construction, convenient in use, strong, and 20 durable.

A further object of the invention is to provide a gang-plow of the above mentioned character, having novel and simple means to regulate the depth that the plow-shares will 25 cut.

A further object of the invention is to provide a self-adjusting draft appliance to connect the gang-plow with a tractor.

Other objects and advantages of the invention will be apparent during the course 30 of the following description.

In the accompanying drawings forming a part of this specification and in which like numerals are employed to designate like parts throughout the same, Figure 1 is a plan view of a gang-plow, embodying my invention, showing the plow-shares arranged to throw the soil outwardly, Fig. 2 is a similar view, with parts adjusted so that the 35 plow-shares will throw the soil inwardly, Fig. 3 is a side elevation of the apparatus, the plow-shares being arranged to throw the soil outwardly, Fig. 4 is a front end elevation of the same, the plow-shares throwing the soil outwardly, Fig. 5 is an enlarged 40 detail section through a sleeve or bearing and associated elements, Fig. 6 is a similar view taken at right angles to Fig. 5, and, Fig. 7 is a detail side elevation of a hinge- 45 member.

The numerals 10 and 11 designate frame-sections, which are identical in all substantial respects. Each frame-section comprises a main longitudinal bar or strip 12, 50 to which is secured a supplemental longitudi-

dinal bar or strip 13, by means to be described.

The numeral 14 designates an outer supplemental bar or strip having its forward end bent laterally, as shown at 15, and bolted 60 or otherwise rigidly secured to the bar 13, as shown at 16. Arranged inwardly of and adjacent the supplemental bar 14, is a reinforcing bar or strip 17, attached thereto, at its ends, by means of bolts 18 or the like, 65 with the ends of the supplemental bar 14, as shown. Arranged between the bars 14 and 17, is an upstanding stock or standard 19, rigidly attached thereto by means of bolts 20 or the like. At its lower end, this stock 70 or standard has a turning plow-share 21, rigidly secured thereto. The rear end of the supplemental bar 14, is bent laterally, as shown at 22, and carries an extension 23, as shown. Arranged between this extension 75 and the rear end of the supplemental bar 13, is a stock or standard 24, rigidly secured to the same by means of bolts 25 or the like. Rigidly attached to the lower end of the stock or standard 24 is a turning plow-share 80 26, as shown. The rear end of the supplemental bar 13 is bent laterally, as shown at 27, and carries an extension 28, arranged in proximity to the rear end of the main bar 12. Arranged between the extension 28 and 85 the rear end of the main bar 12 is a stock or standard 29, rigidly secured thereto by means of bolts 30 or the like. A turning plow-share 31 is rigidly secured to the lower 90 end of the stock or standard 29, as shown. The rear end of the main bar 12 is bent laterally, as shown at 32, and carries an extension 33, disposed in proximity to an inner supplemental longitudinally extending bar 34, having its forward end bent laterally, 95 as shown at 35. The forward portion 35 of the bar 34 carries an extension 36, rigidly attached to the main bar 12, by means of a bolt 37 or the like. Disposed between the extension 33 and the supplemental bar 34 is a 100 stock or standard 38 rigidly secured thereto by means of bolts 39 or the like. At its lower end, this stock or standard carries a turning plow-share 40, as shown.

Attention is called to the fact that all of the plow-shares in the same set, carried by either of the frame-sections, extend in the same direction, for turning the soil inwardly or outwardly, as will be more fully explained.

The numeral 41 designates a bearing or bearings, carrying a laterally offset depending shank 42, (see Fig. 6), adapted to be arranged between the extension 33 and the rear end of the supplemental bar 34. This shank is rigidly and detachably connected with the extension 33 and bar 34, by means of bolts 42' or the like. When the frame-sections 10 and 11 are so adjusted that the plow-shares throw the soil outwardly, as shown in Fig. 1, I employ only one of the bearings 41, which may be carried by either frame-section, but when the frame-sections are adjusted whereby the plow-shares throw the soil inwardly, I employ two of these bearings, one being secured to the rear end of each frame-section in the manner hereinabove described. In considering Fig. 1, the numeral 43 designates a vertical spindle, which is swiveled or journaled within the bearing 41 and held against longitudinal movement therein by any suitable means such as rings 43' rigid thereon. At its lower end, this spindle carries a laterally off-set extension or arm 44, upon the lower end of which is rotatably mounted a ground-wheel 44', as shown. As more clearly shown in Fig. 5, a bracket or support 45 is rotatably or loosely mounted upon the upper end of the spindle 43, below a steering lever 46, rigidly attached to the spindle, as shown. This steering lever extends forwardly with respect to the machine, while a toothed quadrant 47 is rigidly secured to the bracket 45, and extends in an opposite direction.

The numeral 48 designates a vertically swinging lever having its forward portion forked, straddling the bracket 45, and pivoted thereto by means of a bolt 49 or the like. This lever is equipped with latch mechanism 50 for detachable engagement with the teeth of the quadrant 47 whereby the lever may be locked in adjustment at the desired position, as is well known. Pivotedly connected with the forward end of the lever 48 are depending links 51, having their lower ends pivotally connected with the frame-sections 10 and 11, to raise and lower the same, upon swinging the lever 48 in the proper direction. In Fig. 2, each of the frame-sections 10 and 11 carries at its rear end a bearing 42, spindle 43, ground-wheel 44, lever 48, and associated elements. When there are two of these ground-wheels at the rear end of the machine, I may dispense with the steering lever or levers 46.

From the foregoing description, it is obvious that when the parts of the apparatus are adjusted, as shown in Fig. 1, the operating lever 48 and associated elements serve to vertically adjust the rear end of the frame-section, to regulate the depth of cutting of the plow-shares and when the frame-sections are reversed, as shown in Fig. 2, whereby the plow-shares will throw in-

wardly, two of the levers 48 and associated elements are employed to vertically adjust the rear ends of the frame-sections, such adjustment being separately accomplished. Arranged near the forward end of the frame-sections 10 and 11, are vertical bearings 52 identical in all substantial respects with the vertical bearings 41. The bearings 52 are rigidly connected with the forward end of the bars 12, as is obvious. Journaled in the vertical bearings 52 are vertical spindles 53, carrying at their lower ends lateral extensions or arms 54, upon which are rotatably mounted ground-wheels 55, as shown. Rotatably or loosely mounted upon the upper end of the spindles 53, which are identical with spindles 43, are brackets 56 upon which are pivotally mounted vertically swinging levers 57, as shown at 58, the same having means whereby they may be locked in adjustment at the desired position. At their forward ends, these vertically swinging levers 57 have pivotal connection with depending links 59, pivotally connected with the forward ends of the frame-sections, as shown. It is obvious that by raising or lowering the levers 57, the forward ends of the frame-sections 10 and 11 may be raised and lowered, correspondingly regulating the depth that the plow-shares will cut. As these bearings 52, spindles 53 and associated elements are substantially identical with the bearings 41, spindle 43, and associated elements, it is believed unnecessary to further describe the same in detail.

Means are provided to hinge or pivotally connect the frame-sections 10 and 11, whereby they may be adjusted or turned upon their longitudinal axis for laterally inclining the plow-shares, whereby the inner or outer plow-shares will be made to enter the soil for different distances. The pivotal connecting means comprises (see Figs. 1, 2, 3 and 4) approximately vertical hinge-members 61 and 62, rigidly connected in Fig. 1, with the main bars 12 by bolts 63, while in Fig. 2 the same are rigidly attached to the supplemental bars 13, preferably by the same bolts, suitable bolt holes being provided in the bars 13 for receiving the bolts. At their lower ends, the vertical hinge-members 61 and 62 are provided with inward extensions or cranks 64, the ends of which are pivotally connected by bolts 65 or the like. To provide for suitable adjustment, additional bolt holes 66 are provided in the extensions 64, for the reception of the bolt 65, as may be found advantageous. The hinge-members 61 and 62 extend upwardly beyond the frame-sections for a substantial distance as best illustrated in Figs. 4 and 7. Pivotally connected with the upper end of the hinge-members are screw-threaded rods 67, carrying a turn buckle 68, as shown. It is obvious that by rotating the turn buckle 68,

the hinge-members 62 may be swung transversely of the frame-sections in either direction, whereby the frame-sections will be turned upon their longitudinal axes, and locked in adjustment at the desired position for the purpose hereinabove set forth.

The numeral 70 designates draft appliance, as a whole, comprising transverse rods or members 72 and 73, which have pivotal connection with diagonal rods 74, crossing each other as shown. The inner transverse rod 73 is attached to the transverse end bars 13' by strips or members 75, the connection being suitably flexible whereby it does not interfere with the adjustments of the frame-sections 10 and 11, and being detachable to expedite the reversal of the frame-sections. The outer transverse rod 72 is adapted for connection with a tractor (not shown).

I have found that my gang-plow is particularly useful in plowing the alleys between grape-vines, while the same is not restricted to this use.

When the parts of the apparatus are assembled, as shown in Fig. 1, the plow-shares are faced outwardly, whereby they turn the soil outwardly. By rotating the turn buckle 58 the frame-sections 10 and 11 may be turned or adjusted upon their longitudinal axes, causing the outer shares to enter the soil at a greater or less depth, as may be desired.

When it is desired to throw the soil inwardly, the frame-sections 10 and 11 are disconnected, and the section 11 arranged upon the opposite side of the section 10, as indicated in Fig. 2. The hinge means now serve to connect the frame-sections, as shown. Instead of employing one ground-wheel 45, two are used.

It is to be understood that the form of my invention herewith shown and described is to be taken as a preferred example of the same, and that various changes in the shape, size and arrangement of parts may be resorted to without departing from the spirit of the invention or the scope of the subjoined claims.

Having thus described the invention, I claim:

1. In a gang plow of the character described, the combination with a plurality of separate frame-sections adapted to be arranged side by side and reversed with relation to each other, of laterally spaced plow shares carried by each frame section, a plurality of approximately vertical members

to be carried by each frame-section and adapted to extend upwardly and downwardly beyond the same for a substantial distance, means whereby the approximately vertical members may be rigidly and detachably connected with the opposite sides of the frame-section when the frame-section is reversed with relation to the other frame-section, means detachably connecting the lower ends of the opposite approximately vertical members, and means detachably connecting the upper ends of said opposite approximately vertical members.

2. In a gang plow of the character described, the combination with a plurality of separate frame-sections, of laterally spaced turning plow shares carried by each frame-section and facing in the same direction, a plurality of substantially vertical hinge members to be carried by each frame-section and extending upwardly and downwardly beyond the same for a substantial distance, means whereby the hinge members may be rigidly and detachably connected with the opposite sides of the frame-section when the frame-section is reversed with relation to the other frame-section, means pivotally connecting the lower ends of the opposite hinge members, and adjustable means connecting the upper ends of the opposite hinge members whereby the frame-sections may be turned upon their longitudinal axes.

3. In a gang plow of the character described, the combination with a plurality of separate frame-sections, of laterally spaced turning plow shares carried by each frame-section and facing in the same direction, a plurality of substantially vertical hinge members to be carried by each frame-section and extending upwardly and downwardly beyond the same for a substantial distance, means whereby the hinge members may be rigidly and detachably connected with the opposite sides of the frame-section when the frame section is reversed with relation to the other frame-section, means pivotally connecting the lower ends of the transverse pairs of hinge members, and turn buckles connecting the upper ends of the transverse pairs of hinge members, substantially as described.

In testimony whereof I affix my signature in presence of two witnesses.

FRANK S. WILLIAMS.
